UNITED STATES PATENT OFFICE

HAROLD L. DE LISLE, OF CHICAGO, ILLINOIS

CONTAINER FOR SHEETS

Application filed July 16, 1928. Serial No. 293,070.

These improvements relate to containers for sheet material such as blue prints and tracings, and have been designed chiefly for use in the drafting room. The chief object is to provide an envelope, folder or container into and from which the sheets are insertable and removable in a simple, easy and expeditious way and without such bad effects as tearing and abrasion. Other objects and advantages will appear hereinafter.

The sheets in question are substantially large—frequently quite large. It has been customary to place such sheets in drawers within envelopes or folders comprising a single sheet of fairly stout paper folded upon itself, and sometimes with protecting flaps at the sides. In such case the first few sheets at the top may severally be withdrawn or inserted without much effort or bad effects, but when, however, the withdrawal or insertion of sheets well within the body of the mass is attempted, especially at and toward the bottom thereof, notable difficulties arise, and in the effort sheets are torn and there is always destructive abrasion in such sheets as tracings or other original drawings. The present improvements overcome such bad conditions.

In the accompanying drawings Figure 1 is a small perspective showing my improved envelope device or container complete; Fig. 2 shows it on a larger scale in side elevation, with sheet material held therein as for filing away permanently; Fig. 3 fragmentarily shows a cabinet construction with my envelope device in a drawer thereof and in one of its operative positions, the side flaps 18 being omitted; Fig. 4 is a small perspective partly broken away showing the device and sheet material therein ready to be put into storage; and Fig. 5 shows a detail of the construction at one of the lifting devices.

My improved container comprises first an outer and heavy cover member of substantially stiff material. It may be cardboard or sheet-metal. The base 10 is a continuous flat rectangular sheet. There is a rear top section 11, an intermediate top section 12, and a front top section 13, these several top sections being hinged together in series, and section 11 is hinged to the bottom 10 as shown in

Fig. 2, fabric hinges as 14, 15, 16 (Fig. 2) being employed.

At each side edge of the base 10 there is secured, as by glue, a wing or side flap 18 (see Fig. 1), of strong paper or fabric.

55

Within the outer envelope or casing is an inner sheet of thin and flexible material, as strong paper or fabric, marked 20. It is secured at one end by glue to the under surface of the rear upper member 11, extends backward and then forward as a loop and rests on the base 10, its free end portion 20^a extending well forward of the front edge of the base.

In practice the base 10 is deep enough from front to back to accommodate sheets of various sizes. These in a given container are of a given size. The operator adjusts the flexible sheet 20 to act as a stop at the bend 20^b so that the front edges of the sheet material 70 will be maintained at their proper place and the confused situation due to some of the sheets being farther back than others is avoided. Having adjusted the stop at 20^b the flap 20^a is folded under the base 10 as shown in Fig. 3, and becomes held by the bend where it is turned over and by the weight of the container and its contents. This arrangement is maintained so long as the sheet material is in the current file or for any reason is maintained in the drawer.

Secured to each side edge portion of the intermediate cover member 11 are means for raising and lowering the upper or top members of the outer envelope. These means are shown as a leverage device A having a top sheet-metal clip member 22 (Fig. 5) and a bottom sheet-metal clip member 23, said members having indentations at 24 and 25 respectively for better holding effect, these members being spaced apart so as to fit frictionally upon the free edge of the member 11. The device A can be applied and removed readily. The top member 22 turns downward at right angles to form the part 26 and the bottom clip member 23 similarly turns downward to form the part 27. The construction thus comprises two angle irons. Between the parts 26 and 27 is a piece of fibre or similar spacing material 28. Rivets 29 hold the an-

80

100

gle-iron pieces and filler rigidly together. The spacer 28 extends only to the dotted line 30 in Fig. 2, and between the free ends of parts 26 and 27 a roller 31 is pivoted on the pin 32.

Figs. 2 and 5 show this lever device as lying outside the base 10. The roller 28 travels directly upon the bottom of the drawer or other rest surface, as shown in Fig. 3.

Fig. 2 shows the drawer partially withdrawn and a sheet at about the middle of the mass exposed. In that position the operator may desire either to withdraw the top sheet or insert a sheet. In order to bring about the relative positions of Fig. 3 the operator began with the device positioned as in Fig. 2 (except that the flap part 20^a was turned under the base 10 as shown in Fig. 3). He first found the space where he wanted to withdraw or insert the sheet. Then, by holding the upper portion of the sheet material and the cover leaf together, he folded the two upward on the hinge 16, turning the leaf 13 over upon the intermediate leaf 12. He then folded the cover member at the hinge 15.

The roller 31 is rearward beyond the hinge 15. The last turning, folding or rolling-over movement automatically resulted in raising or lifting the hinge at 15 and, consequently, the cover as a whole and the sheet material folded with parts of it. The folded parts lean or rest against the front of the cabinet, as shown in Fig. 3.

There is thus provided not only a large open space whereby much of a sheet temporarily to be examined is exposed and whereby the inserting and withdrawing operation is facilitated, but the weight is removed from the topmost sheet except close to the stop 20^b. The operator can simply lift off the topmost sheet, take it away for examination, and then slip it back into place, or slip another into place, turning back the folded lid parts and sheet material when he is through.

Such sheet material usually in time loses its usefulness for current operations and it is then placed in storage. When that time arrives, the outer envelope and its contents are removed bodily from the drawer, the flaps 18 turned over so as to lie on top of the sheets to cover the side edges thereof, and the front end 20^a of the other protector is turned over on top of the sheets and flaps 18 as shown in Fig. 4. Thereupon the outer parts 11, 12 and 13 are laid down as shown in Fig. 4.

There is thus produced a strong envelope or container which does not buckle or bend much in handling, but maintains the material flat, with protecting flaps over and around the edges of the sheet material; and this unit may conveniently be filed away in the permanent drawer or shelf. The unit occupies but little space beyond that actually

required by the sheet material itself. Such units may be piled one upon another and, owing to the strength of the container, may be pulled out from time to time for consultation.

It is not necessary to remove the lifting devices when placing the unit in storage. That may be done if desired, but such lifters can readily be applied at the time consultation is again desired.

My improved container effects a great saving of time and effort and affords highly increased protection in various ways. It is simple in construction and convenient in operation, and the cost is small.

I contemplate as being included in these improvements all such variations, changes and departures from what is thus specifically illustrated and described as fall within the scope of the appended claims.

I claim:

1. A sheet container of the character described for holding loose sheets in a stack and comprising a flat sheet-like base of substantially strong material, and a lid or cover member of strong sheet-like material and substantially coextensive with the base, the cover member comprising at least three laterally-extending sections flexibly connected together side by side in series, the rear section and base being flexibly connected adjacent to their rear edges respectively and the front section being substantially narrow with respect to the rear section.

2. The combination of claim 1 hereof together with a sheet of thin and flexible material secured to one of the top sections and extending rearward and then forward so as to lie to a large extent on the base, the free end of said sheet extending beyond the base and being adapted to fold under the base in one use and around the edge of sheet material within the device in another use.

3. The combination of claim 1 hereof together with side flaps on the base adapted to fold upon and around edge portions of sheet-material within the device.

4. The combination of claim 1 hereof together with means for automatically raising top sections of the envelope and sheet material carried thereby by folding therewith when one of the envelope sections is turned upward and rearward on a hinge connection thereof.

5. The combination of claim 1 hereof together with means readily applicable to and removable from side edge portions of one of the upper sections providing a lever action for elevating sections of the cover when the cover sections are normally operated as to expose sheets in the devices, said means constituting a support for maintaining sections of the cover elevated when it is desired to insert or remove sheets.

6. A device of the character described

comprising a strong sheet-like base on which
sheets may be piled in a stack, a plurality
of substantially strong cover members ex-
tending from side to side above the base
5 and hinged together in series from back
to front, the rearmost one being hinged also
to the rear edge of the base, and means at
the sides of an intermediate one of said mem-
bers for supporting that cover member and
10 associated cover members in an elevated po-
sition.
